INSERT BOARD

Benjamin Liebowitz, New York, N. Y., assignor to
 Trubenizing Process Corporation, New York,
 N. Y., a corporation of New York

Application August 5, 1950, Serial No. 177,952

6 Claims. (Cl. 223—71)

1

This invention relates to a folding or insert board for shirts as finished by the manufacturer of the shirts and as sold in the shops. It is also applicable to shirts as finished by commercial laundries.

An object of this invention is to eliminate or at least minimize deformation of the collar, particularly the upward curling of the collar points, which is a common fault in shirts as delivered to the consumer today.

Most shirts today are sold with the collars pressed standing up or erect, i. e., with the neck band more or less perpendicular to the plane of the pressed body. In this conformation, the points of the collar cannot extend straight out from the neck band but must take an upward curvature which to a large extent spoils the appearance of the shirt in the hand and unless corrected by the wearer before donning the shirt will make the points stand away from the body of the wearer in an unsightly manner.

This difficulty can be avoided by adequately slanting the front region of the neck band so that it makes a relatively obtuse angle with the plane of the pressed body of the shirt.

The problem is to achieve this slanting of the front portion of the neck band and thus to eliminate the undesirable curvature of the points, but at the same time the cost must be kept very low. I achieve this objective by a very simple form of folding or insert board in which the collar is supported and lifted away from the body in approximately the middle regions thereof, as will be understood from the following drawings in which:

Fig. 1 is a perspective view of a conventional folded shirt with the collar erect, as customarily seen in the stores, i. e., showing the undesirable curvature of the collar point;

Fig. 2 is a perspective view corresponding to Fig. 1, showing the appearance of the shirt when the undesirable curvature of the collar points is eliminated;

Fig. 3 is a perspective view of one form of my new shirt insert board showing how supports for the collar are obtained from the stock of the board itself and indicating by a dotted line the location of the board in the folded shirt;

Fig. 4 is a plan view of the board shown in Fig. 3 with the left side showing the board as punched and the right side showing how the punched part is bent up to form the support;

Fig. 5 is a plan view of a detail of a modified board as cut or punched;

Fig. 6 is a cross-section on the line 6—6 of Fig. 5 showing how the collar support is obtained by bending up the punched part of the board;

2

Fig. 7 is a plan view illustrating a modification in which the collar support is obtained from a part extending beyond the body portion of the board;

5 Fig. 8 is a plan view; and

Fig. 9 is an end view showing a further modification in which the collar support is obtained from a separate piece of stock;

Fig. 10 is a plan view; and

10 Fig. 11 is an end view of still a further modification in which the collar support is also obtained from a portion extending beyond the body portion of the board;

Fig. 12 is a plan view; and

15 Fig. 13 is an end view of another modification in which the collar support is obtained by bending up the body portion of the board as a whole;

Fig. 14 is a plan view; and

20 Fig. 15 is an end view of still another modification in which the collar support is obtained from two small separate pieces of stock;

Fig. 16 is a cross-section showing how the collar support material may be serrated in a certain region in order to obtain smooth curvature;

25 Fig. 17 illustrates a desirable form of tongue;

Fig. 18 a desirable form of slot for locking the collar support portion after it is bent into shape; and

Fig. 19 illustrates the interlocking arrangement of the tongue and slot of Figs. 17 and 18.

30 Referring to the drawings:

Fig. 1 is a perspective view of a shirt as conventionally folded and as sold in the stores, exhibiting an undesired concave curvature of the collar points in the region A—A.

35 Fig. 2 shows how the same shirt will appear when the collar is properly supported so as to avoid the curvature referred to.

Fig. 3 is a perspective view corresponding to

40 Figs. 1 and 2 showing how the curvature of the collar points can be eliminated or minimized so as to achieve the appearance shown in Fig. 2, by means of an insert board 10 from the body of which flaps are cut out, these flaps being then

45 bent to take the position and form as shown at 11, so that the said flaps form an arch or bridge or support on which the bottom of the side portions of the collar will rest so as to lift the pressed collar away from the plane of the shirt.

50 I wish to note that the term "collar" as used above and in the following description and claims includes the fold-over portion of the collar and/or the collar band thereof. Actually, it is sufficient to support either the fold-over portion or the collar band but preferably, both the fold-over

55

portion and the band are supported by the supporting means described above.

The arched form of the support 11 is obtained by simple means which will be presently explained. The region of contact between the bottom of the collar and the bridge 11 is determined by the proper placing of the said supports 11 and is chosen so that the said points of support will come more or less between the tie space of the collar and the joining seam shown at J in Figs. 1 and 2. The region of support is intended to lie approximately on the dotted line S shown in Fig. 2.

I have found it preferable to arrange the supporting means so that their supporting top portions, e. g. supporting ridge portions, are located between two and three inches from the transversal rear edge of the board, substantially parallel to the same and between one quarter and three quarters of an inch above the level of the board. Very good results were obtained with an insert board in which the ridges of the supports are located at a distance of about two and one half inches from the transversal rear edge of the board and about one half of an inch above the level of the same.

Referring to Fig. 4, the body portion, i. e. the flat board member forming part of the insert board may be cut through to form flaps as shown at the left at 11A and to form a tongue on the flap as shown at 11B. Likewise slots 12 are cut into the board below the top edge thereof. The board is scored along the dotted line 11C as shown again at the left of Fig. 4. After the board has been completely punched out, the flaps 11A can be bent up into the position shown at 11 on the right side of Fig. 4, with the tongue 11B pushed into the slot 12. By making the length of the flap 11A longer than the distance from the scored line 11C to the far edge of the slot 12, the flap 11 takes an arched position, as indicated in Fig. 3.

Improved mechanical support for the arch 11 may be obtained, as shown in Figs. 5 and 6, by punching through an auxiliary tongue 13 with the score at 13C and subsequently bending the auxiliary tongue downward so that the tongue thereof, viz., 13B, enters the slot 14. Whether or not the auxiliary tongue 13 and slot 14 are used, the cross-section of Fig. 6 indicates the general shape taken by the flap 11A to form the bridge or support 11 for the collar.

In order to avoid puckering of the shirt in the neighborhood of the shoulders as a result of the presence of the supports 11, I prefer to cut away slightly the portions of the board indicated at 15, as shown in Figs. 4 and 5.

The form of board illustrated in Figs. 3 to 6 inclusive has the advantage that it requires no extra stock because the flaps that form the support are punched from the body material of said board. In some instances it may be preferable not to weaken the board in this manner. In that event the form illustrated in Fig. 7 can be used, which will be readily understood by reference to the foregoing description.

Referring now to the modifications shown in the remaining figures, in Figs. 8 and 9, the collar support or bridge is obtained by cutting an extra piece shown at 21 which has tongues 21B which are inserted into slots 22 to form the bridge or support as indicated.

In the modification shown in Figs. 10 and 11, the collar support is obtained by means of a portion of the board which extends beyond the body

portion and is bent and scored as shown at 31, the bridge being held in position by means of tongues 31B fitting into slots 32.

In the modification shown in Figs. 12 and 13, the bridge for the collar is obtained by scoring the body of the board along the lines T and then bending the board to form the bridge, as shown at 41, in Fig. 13, and maintaining in the shape thus given to it by means of an additional strip of board shown at 45, which may be pasted or stapled to the body portion of the board.

In the modification shown in Figs. 14 and 15 the bridge is obtained from two small separate pieces of board, as indicated at 51A and 51B.

The ridge of the supporting bridge may form a relatively sharp corner but it is preferable to have it form a smooth curve. This can be facilitated by scoring the board as shown in Fig. 16 at K and as indicated likewise in Figs. 4 and 7 by the symbol K.

Figs. 17, 18 and 19 are enlarged fragmentary views showing a suitable form of tongue 11B and slot 12.

Fig. 19 shows how the tongue 11B and slot 12 lock to hold the bridge or support securely in position once the tongue has been engaged in the slot.

What I claim is:

1. An insert board for men's shirts comprising in combination, a generally flat board member having a transversally extending sharp rear edge and opposite side edges; and at least one upwardly projecting support on said flat board member arranged spaced from both said rear edge and said opposite edges of said board member and located with its top portion spaced from said sharp rear edge of said flat board member at a distance substantially equal to half of the distance between the front and rear edges of the collar of a shirt to be supported by said insert board so as to support and thereby raise the bottom edges of said collar at opposite sides thereof above the level of said flat board member while said sharp rear edge of the board member forms a sharp crease along the shoulders of the shirt.

2. An insert board for men's shirts comprising in combination, a generally flat board member having a transversally extending sharp rear edge and opposite side edges; and at least one upwardly projecting transversally extending support on said flat board member arranged spaced from both said rear edge and said opposite side edges of said board member and having a transversally extending top portion spaced from said sharp rear edge of said flat board member at a distance substantially equal to half of the distance between the front and rear edges of the collar of a shirt to be supported by said insert board so as to support and thereby raise the bottom edges of said collar at opposite sides thereof above the level of said flat board member while said sharp rear edge of the board member forms a sharp crease along the shoulders of the shirt.

3. An insert board for men's shirts comprising in combination, a generally flat board member having a transversally extending sharp rear edge and opposite side edges; and upwardly projecting supporting means on said flat board member arranged spaced from both said rear edge and said opposite side edges of said board member and having top portions located from said transversally extending sharp rear edge of said insert board at a distance of between two and three inches therefrom and at least in those

regions of said flat board member which are normally located under the side portions of the collar of a shirt supported by said insert board, so as to support and thereby raise the bottom edges of said side portions of said collar above the level of said flat board member while said sharp rear edge of the board member forms a sharp crease along the shoulders of the shirt.

4. An insert board for men's shirts comprising in combination, a generally flat board member having a transversally extending rear edge including at both ends of said rear edge inclined sharp edge portions forming obtuse angles with the opposite side edges of said flat board member; and two upwardly projecting supporting means on said flat board member, each arranged spaced from both said rear edge and said opposite side edges of said board member, extending substantially parallel to one of said inclined sharp edge portions of said rear edge of said flat board member and located at least in those regions of said board member which are normally disposed under the side portions of the collar of a shirt supported by said insert board, so as to support and thereby raise the bottom edges of said side portions of said collar above the level of said flat board member while said inclined sharp edge portions of said rear edge of the board member form a sharp crease along the shoulders of the shirt.

5. An insert board for men's shirts comprising in combination, a generally flat board member having a transversally extending rear edge including at both ends of said rear edge inclined sharp edge portions forming obtuse angles with the opposite side edges of said flat board member; and two upwardly projecting elongated supporting means on said flat board member, each arranged spaced from both said rear edge and said opposite side edges of said board member and having a ridge extending substantially parallel to one of said inclined sharp edge portions of said rear edge of said flat board member spaced

from the same at a distance of between two and three inches, so as to support and thereby raise the bottom edges of the side portions of the collar of a shirt supported by the insert board above the level of the same while said inclined sharp edge portions of said rear edge of the board member form a sharp crease along the shoulders of the shirt.

6. An insert board for men's shirts comprising in combination, a generally flat board member having a transversally extending sharp rear edge and opposite side edges; and at least one supporting flap formed within said flat board member by an incision arranged spaced from both said rear edge and said opposite side edges of said flat board member and being connected to the said flat board member along a hinge edge extending substantially parallel to and spaced from said rear edge of said board member, said supporting flap being bent along said hinge edge above the plane of said flat board member and attached at its opposite free edge to said flat board member so as to form upwardly projecting supporting means arranged at least in those regions of said flat board member which are normally located under the side portions of the collar of a shirt supported by said insert board, so as to support and thereby raise the bottom edges of said side portions of said collar above the level of said flat board member while said sharp rear edge of the board member forms a sharp crease along the shoulders of the shirt.
